UNITED STATES PATENT OFFICE.

HAROLD M. BRAYTON, OF DOVER, NEW JERSEY.

POINT-DETONATING FUSE.

Application filed August 5, 1924. Serial No. 730,296.

(GRANTED UNDER THE ACT OF MARCH 3, 1883; 23 STAT. L. 625.)

To all whom it may concern:

Be it known that I, HAROLD M. BRAYTON, a citizen of the United States, and a resident of Dover, county of Morris, and State of New Jersey, have invented an Improvement in Point-Detonating Fuses, of which the following is a specification.

The invention described herein may be used by the Government, or any of its officers or employees in prosecution of work for the Government, or by any other person in the United States, without payment to me of any royalty thereon, in accordance with the act of March 3, 1883.

The subject of this invention is a point detonating fuse.

The object of the present invention is to provide a bore safe supersensitive point detonating fuse in which the various elements are so arranged as to produce a practical mechanism for manufacture and assembly which will function dependently when fired from a gun.

According to the invention, the booster charge is carried in a separate container for the purpose of eliminating body distortion in the booster loading operation and also with the object of insuring safety in assembling, as the booster container is the last element to be assembled.

In that type of fuse which is characterized by a movable striker head positioned in the nose of the fuse, considerable difficulty has been encountered in the usual crimping operation, with the result that the striker is frequently held immovable and the fuse accordingly rendered inoperative. To overcome this objection, an annular cap is formed with a fixed inturned rim and the cap held in place by crimping the body.

There is also provided a centrifugally released rotor which positively prevents premature explosion during storage and transportation.

To these and other ends, my invention consists in the construction, arrangement, and combination of elements, described hereinafter and pointed out in the claims forming a part of this specification.

A practical embodiment of my invention is illustrated in the accompanying drawings, in which,

Fig. 1 is a longitudinal sectional view of the improved fuse taken on the line 1-1

of Figure 3 and showing the parts in safety 55 or unarmed position;

Fig. 2 is a sectional view taken on the line 2-2 of Fig. 4;

Fig. 3 is a sectional view taken on the line 3-3 of Fig. 1; and

Fig. 4 is a sectional view taken on the line 4-4 of Fig. 1 but showing the rotor in armed position.

Referring to the drawings by numerals of reference:

A body 10 formed with an eccentric cavity 11 is tapped to receive a container 12, which carries a booster charge 13 spaced from the cavity by a cup 14.

The cavity 11 is approximately in the 70 longitudinal center of the fuse and houses a rotor 15, loosely mounted on a pin 16 which is carried by the body 10, as seen in Figure 2.

The rotor is approximately T-shaped and 75 is normally held in safety or unarmed position by centrifugal pins 17 to dispose a blind cavity 18 axially of the fuse.

One wing of the rotor is formed with an aperture 19 throughout its length to frictionally retain a cup 20, which carries a primer detonator 21. When in unarmed position the primer detonator is out of line with the center of the fuse.

The opposite wing of the rotor is formed 85 with a slot 22 for the reception of a locking pin 23 which is adapted to be thrown outward through centrifugal force to engage in a slot 24 in the body 10 to hold the rotor in armed position with the detonator 21 in line with the booster charge and a firing pin. The slots 22 and 24 are aligned by means of a stop pin 25, carried by the body and projecting into the cavity to engage a recess 26 formed in a wing of 95 the rotor.

The forward face of the body 10 is formed with an annular groove 27 for the reception of an annular cap 28, which is held in place by crimping the body as at 29.

The cap 28 is formed with a fixed inturned rim 30 for the purpose of confining and limiting the forward movement of a hollow striker head 31 forming the nose of the fuse and provided with an annular flange 32. The central portion of the exterior face of the striker is depressed as at 33 to merge with a stem 34, which car-

ries a fixed firing pin 35 adapted to move in an opening 36 in the fuse body. When in unarmed position the point end of the firing pin is disposed in the blind cavity 18 of the rotor. The striker is provided near the base of the depression 33 with a plurality of diagonal ports 37 for permitting influx of air into the striker during flight of a projectile. The wall of the striker is provided with apertures 38 which are in advance of the cap 28 when in armed position.

In operation, while the projectile is in the bore of the gun, the striker head is held in rearward position through linear acceleration. Immediately upon leaving the gun, the influx of air through the ports 37 will cause the striker head to move forwardly until extruded where it will be held by the static air pressure developed within the striker. The air pressure exerting a constant force in all directions overcomes dynamic pressure on the exterior face of the striker.

As the striker is extruded to functioning position, the point end of the firing pin carried thereby is moved clear of the blind cavity of the rotor. The centrifugal pins of the rotor are moved outward when the projectile attains a predetermined rotational velocity in flight, thereby enabling the rotor to swing to armed position with the primer detonator 21 disposed axially of the fuse.

It will be noted that by crimping the body of the fuse as at 29, and providing a fixed inturned rim 30, there can be no interference tending to render the movable striker head inoperative. Furthermore, as the booster is separately loaded and secured to the body as a final step in the assembling operation, the casing of the fuse will not be distorted during the loading operation and an additional element of safety is consequently provided.

While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

I claim:

1. A fuse including a body formed with an eccentric cavity, a centrifugally released rotor mounted in the cavity, said rotor provided with a primer detonator and a blind

cavity, said body being further formed with an annular groove in its forward face, an annular cap firmly held in the groove and formed with a fixed inturned rim, an air balanceable striker head movable within the cap, a fixed firing pin carried by the striker, the point end of said firing pin being normally disposed in the blind cavity but adapted to be withdrawn therefrom before rotation of the rotor, and a booster container threadedly secured to the body and closing the cavity.

2. A fuse including a body formed with an eccentric cavity in the approximate longitudinal center of the fuse, a centrifugally released safety member rotatable in the cavity, a primer detonator carried by said member, a separately loaded booster container adapted to complete the fuse in assembling for holding the safety member in place, said body being further formed with an annular groove in its forward face, an annular cap firmly held in the groove and formed with a fixed inturned rim, and an air balanceable striker head movable within the cap.

3. A fuse including a body formed with an eccentric cavity, a centrifugally released safety member rotatable in the cavity, a separately loaded booster container adapted to complete the fuse in assembling for holding the safety member in place, said body being further formed with an annular groove in its forward face, an annular cap disposed in the groove and secured by crimping the body, said cap provided with a fixed inturned rim, and a movable member within the cap.

4. A fuse including a body, said body being formed with an annular groove in its forward face, an annular cap disposed in the groove and held in place by crimping the body, said cap provided with a fixed inturned rim, a movable member within the cap, and a booster container adapted to be separately loaded and threaded to the rear portion of the body as the final step in assembling the fuse.

5. A fuse including a body, said body formed with an annular groove in its forward face, an annular cap disposed in the groove and held in place by crimping the body, said cap provided with a fixed inturned rim, and a member movable within the cap and adapted to be limited in movement by the inturned rim of the cap.

HAROLD M. BRAYTON.
